CLAIM

The ornamental design for an interdental device, as shown and described.

DESCRIPTION

FIG. 1 is a top perspective view of an interdental device showing my new design;

FIG. 2 is a right side elevation thereof, the side opposite being a mirror image;

FIG. 3 is a rear elevation thereof, the side opposite being a mirror image;

FIG. 4 is a top plan view thereof; and,

FIG. 5 is a bottom plan view thereof.

The broken lines shown in the drawings are included for the purpose of illustrating environmental structure and form no part of the claimed design.
